FIREARM.

David M. Williams, Godwin, N. C.

Original application December 13, 1939, Serial No. 308,929. Divided and this application July 19, 1943, Serial No. 495,255

4 Claims. (Cl. 42-3)

This invention relates to firearms and particularly those of the type wherein the energy of the explosion of cartridges of varying lengths or energy and power is used to perform the operations incident to reloading the firearm in preparation for the next shot.

This application is a division of applicant's copending application, Serial Number 308,929, filed December 13, 1939 and issued as Patent No. 2,336,146, December 7, 1943.

It is to be understood, however, that the invention may be applied to any type of firearm including, for example, rifles, shotguns, machine guns, hand guns, etc., these being merely illustrative.

In an autoloading firearm of the type wherein a single shot is to be fired at a time, it is desired that positive means be provided to prevent more than one shot to be fired at a single pull of the trigger.

It is also important and desirable that the firearm be so designed and constructed as to be easily and cheaply manufactured and assembled and simple to take apart and reassemble.

These and other objects will appear in the following description and drawing which are merely illustrative.

In the drawing:

Fig. 1 is a fragmentary sectional elevation with the action open and a cartridge ready to be carried into the chamber by the bolt on the closing motion thereof.

Fig. 2 is a fragmentary sectional elevation with the action closed, a long cartridge being shown in the chamber.

Fig. 3 is a fragmentary view of a modification of a trigger connection.

Fig. 4 is a fragmentary view of a modification of a trigger connection.

The present invention will be described as applied to the conventional .22-caliber rifle for shooting short and long cartridges, although it is distinctly understood not to be limited thereto. In Fig. 1, the usual barrel 20 is shown having a threaded engagement 21 with the receiver 22, in which the bolt 23 is slidably mounted. The bolt 23 is provided with extractors 24. A striker 28 (Figs. 1 and 2) is carried in a suitable aperture in the bolt 23, said striker having a head 29 that is engaged by the striker spring guide means 30. A striker spring 31 acting upon the head 30 of the guide means urges the striker to firing position, the opposite end of said spring abutting end 32 of the tubular guide means 35 located in the plug 33. The plug 33 may be removably connected by

means of screw threads 34 to the receiver 22. The tubular guide means 35 is mounted in the plug 33 so that it may have a loose movement to properly allow for alignment thereof with the bore 36 of the bolt 23 and the other parts cooperating therewith. A bushing 33a may be placed inside of plug 33 if desired, which may be of metal or fiber. A recoil spring 37, located on the outside of the guide means 35, surrounds the tubular guide means 35 and one end thereof has abutting engagement with the interior of the plug 33 as at 38 and the other end with the bolt at shoulder 39. The striker spring is located between the shank of the striker spring guide means 30 and the interior bore of the tubular guide means 35. In this manner, the springs are properly guided and confined in their motion.

Trigger and sear

20 The striker 28 is provided with a suitable sear notch 40 which is adapted to engage the pivoted sear 41, said sear being pivoted on pin 42. The sear 41 has a spring 43 serving to rotate the sear to effective position holding the striker, said spring 10 abutting the receiver at 44. The projection 47 of sear 41 is suitable for engagement with the notch 48 of the pivoted lever 49, said lever being pivoted as at 50 on the trigger 51, a spring 52 serving to rotate the lever 49 in a counterclockwise direction, as viewed in Figs. 1 and 2. In Fig. 1, the lever 49 is shown as it has been rotated in a clockwise direction by retraction of the bolt 23. The notch 48 has converging upper and lower walls so that as projection 47 is moved therein there will be no play between these parts.

In Fig. 2, the projection 47 is shown engaged in the notch 48 of the lever 49, and the sear notch 40 engaged by the sear in cocked position, such that a pull upon the trigger will cause the pivoted lever 49 to be pulled downwardly, thereby rotating the sear 41 in a clockwise direction to disengage it from the notch 40 of the striker 28, thereby allowing the cocked striker spring to move the striker to fired position. The trigger spring 45 33 is carried in a suitable aperture 54 in the trigger:

Assuming that the parts are in the cocked position with the action closed, as shown in Fig. 2, a pull on the trigger 51 will rotate the trigger about its pivot 45, which will move lever 49 downwardly, thereby rotating sear 41 in a clockwise direction and disengaging it from the sear notch 40. Such disengagement allows the cocked striker spring 31 to move the striker to the fired position whereby the point thereof engages the

cartridge in the chamber. Backward or retractive movement of the bolt 23 engages the striker 28 with the tip 55 of the lever 49, rotating it in a clockwise direction, and disengaging the projection 47 of sear 41 from the notch 48 of the lever 49. This allows the sear spring 43 to rotate the sear 41 in a counterclockwise direction, or to urge it to the effective position, so that as the bolt goes forward to its closed position again, the sear notch 40 will engage the sear 41. As the bolt goes forward, the spring 52 will cause the lever 49 to rotate in a counterclockwise direction until it again assumes the position in Fig. 2. It can be seen that if pressure has still been maintained on the trigger 51, that the lever 49 will be in a downward or pulled position, and the notch 48 will not then register with the projection 47 of the sear 41 so that engagement will not take place, and therefore the weapon will not fire a second time. Engagement of the notch 48 with the portion 47 will not then occur until the pressure on the trigger 51 is released, which will then allow the spring 53 to rotate the trigger 51, so that the notch 48 will again be aligned with the projection 47 of the sear. The spring 52 will complete the engagement thereof of projection 47 in notch 48, and as the projection 47 of the sear moves into the converging notch 48, all the play will be removed from the connection. The action of the trigger then will be directly transmitted to the sear without slack. It can be seen that the pulling of the trigger, and maintaining it in the pulled or fired position, will pull the lever 49 downwardly so as to disturb the alignment of notch 48 with projection 47 of the sear after the sear has been released by the trigger through lever 49, thus making it necessary to release the trigger to fire each shot. The use of the converging walls, parts or similar means to take the play out of the trigger mechanism train may also be applied to other portions of the connection and to other kinds of trigger connections. A modification of this is shown in Fig. 3, wherein 104 may be a trigger pivoted at 105 and having a connecting link 106 which may operate the sear. A converging wall aperture 107 is placed in the arm of trigger 104 and a pin 108 is mounted on link 106 which cooperates with the aperture 107. A spring and plunger assembly 109 serves to rotate link 106. This also pushes the link to the left, forcing pin 108 into the converging wall portions in the direction of convergence of aperture 107, so that the play or slack is removed from the trigger mechanism train. It is evident that a connection such as this may be used in other portions of the trigger train and is not limited to that shown. It is also evident that the aperture or recess may have straight walls and the part cooperating therewith have diverging walls to take up the slack. This is shown in Fig. 4 wherein the sear is indicated at 110 with the pivot 111 and sear notch 112. The pivoted lever 113 is pivoted at 114 on the trigger fragmentarily shown at 115. The pivoted lever 113 may have the straight wall connection 116 which mates with the converging margins 117 of the sear 110.

Summary of operation

Assuming that the gun is in the position shown in Fig. 2 with the action closed and the cartridge within the chamber, release of the sear 41 by operation of the trigger 51, such release taking place through the lever 49, notch 48, projection 47, will allow the striker spring 31 to force the

striker forward and fire the cartridge. Assuming further that a long cartridge is in the chamber having sufficient power to operate the parts satisfactorily, as explained more fully in the aforesaid Patent No. 2,336,146, the explosion of the cartridge will force the actuator and bolt rearwardly from the position in Fig. 2, the cartridge case being carried with the actuator and the gas contact area on face 73 remaining sealed. The bolt 23, which is held against the actuator 56, is carried rearwardly therewith and has its recoil motion initiated thereby. The bolt continues in its rearward movement, compressing the recoil spring 31, the recoil spring being so designed that the bolt is stopped approximately just before it reaches the bushing 33A, or, if it does contact the same, to hit the same with but little force, the energy of the recoiling bolt having been practically all absorbed in the compression of the spring together with the compression of the striker spring 31. The rearward movement of the bolt carries the striker 28 therewith, carrying the striker spring guide 39 rearwardly, thereby compressing the spring 31 and moving the striker far enough to the rear so that on the return motion the notch 40 will engage the sear 41 which has been released from engagement with lever 49 and carried to effective position by spring 43. The lever 49 has been rotated about its pivot by the recoil of the bolt, thereby disconnecting the notch 48 from the projection 47.

During the recoiling movement of the bolt, the cartridge case is gripped by the extractors 24 on either side, which hook over the rim of the case in the conventional manner, carrying the cartridge rearwardly, and is ejected by contact with the ejector 79.

The recoil spring having been compressed and the bolt having reached the end of its travel, the energy stored in the recoil spring starts the bolt forward to closed position, and in this movement carries the fresh cartridge into the chamber of the gun ready for the next firing operation. The new cartridges contained in the magazine are moved upwardly by the follower 89 under the urging of follower spring 90, and held in position by means of the co-action of rim 93 (Fig. 1) of the new cartridge with the inturned lips of the retainer. Forward motion of the bolt 23 will engage rim 93, moving the new cartridge forwardly, and when rim 93 is opposite the slot 94 of the retainer, the spring and follower will move the new cartridge above the retainer and into alignment with the chamber, the bolt then in its continued closing motion carrying the cartridge into the chamber. The forward movement of the bolt allows the lever 49 to be rotated in a counterclockwise direction so that when the trigger is released the notch 48 will be aligned with the projection 47 of the sear and place the gun in readiness for the next shot to be fired upon again pulling the trigger.

It is apparent that the invention is not limited to the use in a shoulder rifle as shown, but may be used in any type of firearm, such as a hand weapon or a machine gun. A gun which is easy to manufacture and assemble and which has an improved trigger mechanism has been provided. The embodiments of the invention as herein described are to be understood as typical and illustrative only, said invention being susceptible to the embodiments in many forms, all falling within the scope of the appended claims.

What is claimed is:

1. In an autoloading firearm, a reciprocating

breech block, firing means carried by said breech block, a sear, means on said sear constructed and arranged to engage said firing means for holding the same in a restrained position, a sear spring tending to move the engaging means of said sear to a firing means restraining position, a pivoted trigger, a lever pivoted on said trigger, said lever having a notch with slightly outwardly diverging margins arranged to fit over an end portion of said sear, the width of said end portion being intermediate the widths at the outer and inner ends of said notch, whereby operation of the trigger serves to move the engaging means of the sear into firing means releasing position, and means on said breech block to engage said lever when the breech block is reciprocated rearwardly, thereby enabling said sear spring to move the engaging means of said sear to firing means restraining position and to displace said end portion of said sear out of alignment with said notch when the lever is in trigger operated position.

2. In an autoloading firearm, a reciprocating breech block, firing means carried by said breech block, a sear, means on said sear constructed and arranged to engage said firing means for holding the same in a restrained position, a sear spring tending to move the engaging means of said sear to a firing means restraining position, a pivoted trigger, a lever pivoted on said trigger, said lever and sear being separably engageable, one of said last two mentioned parts having slightly diverging margins and the other of said parts having margins engageable by said slightly diverging margins and defining a width intermediate the widths at the outer and inner ends of the slightly diverging margins, whereby operation of the trigger serves to move the engaging means of the sear into firing means releasing position, and means on said breech block to engage said lever when the breech block is reciprocated rearwardly, thereby enabling said sear spring to move the engaging means of said sear to firing means restraining position and to displace said part having slightly diverging margins out of alignment with the margins of the other part when the lever is in trigger operated position.

3. In an autoloading firearm, a reciprocating breech block, firing means carried by said breech block, a sear, means on said sear constructed and arranged to engage said firing means for holding the same in a restrained position, a sear spring tending to move the engaging means of said sear to a firing means restraining position, a pivoted trigger with an arm having an aperture defining converging margins, a connecting lever between said sear and trigger for actuating said sear, said lever having means ar-

ranged to be wedged between said converging margins of said aperture, spring means urging said lever means into wedging engagement with the converging margins of said aperture and in the direction of convergence thereof whereby lost motion is eliminated between the trigger and connecting lever, said connecting lever having a notch with slightly outwardly diverging margins arranged to fit over an end portion of said sear, the width of said end portion being intermediate the widths at the outer and inner ends of said notch, whereby operation of the trigger serves to move the engaging means of the sear into firing means releasing position, and means on said breech block to engage said lever when the breech block is reciprocated rearwardly, thereby enabling said sear spring to move the engaging means of said sear to firing means restraining position and to displace said end portion of said sear out of alignment with said notch when the lever is in trigger operated position.

4. In an autoloading firearm, a reciprocating breech block, firing means carried by said breech block, a sear, means on said sear constructed and arranged to engage said firing means for holding the same in a restrained position, a sear spring tending to move the engaging means of said sear to a firing means restraining position, a pivoted trigger with an arm having an aperture defining converging margins, a connecting lever between said sear and trigger for actuating said sear, said lever having means arranged to be wedged between the converging walls of said trigger arm aperture, spring means urging said lever into wedging engagement with the converging margins of said aperture and in the direction of convergence thereof, whereby lost motion is eliminated between the trigger and connecting lever, said lever and sear being separably engageable, one of said last two mentioned parts having slightly diverging margins and the other of said parts having margins engageable by said slightly diverging margins and defining a width intermediate the widths at the outer and inner ends of the slightly diverging margins, whereby operation of the trigger serves to move the engaging means of the sear into firing means releasing position, and means on said breech block to engage said lever when the breech block is reciprocated rearwardly, thereby enabling said sear spring to move the engaging means of said sear to firing means restraining position and to displace said part having slightly diverging margins out of alignment with the margins of the other part when the lever is in trigger operated position.

DAVID M. WILLIAMS.
